DESIGN FOR AN EARRING HOLDER

Shirley Carol Nissen and Charles E. Nissen, Maywood, N. J.; Margaret Nissen, administratrix of said Charles E. Nissen, deceased, assignor to said Shirley Carol Nissen

Application February 27, 1946, Serial No. 126,950

Term of patent 7 years

(Cl. D80—9)

To all whom it may concern:

Be it known that we, Shirley Carol Nissen and Charles E. Nissen, both being citizens of the United States, residing at Maywood, in the county of Bergen and State of New Jersey, have invented a new, original, and ornamental Design for an Earring Holder, of which the following is a specification, reference being had to the accompanying drawings, forming a part thereof, in which:

What we claim is:

The ornamental design for an earring holder, as shown.

SHIRLEY CAROL NISSEN.
CHARLES E. NISSEN.
